UNITED STATES PATENT OFFICE.

ALEXANDER D. CROSS, OF NEWARK, NEW JERSEY, ASSIGNOR OF ONE-HALF TO
GUSTAVE H. SHAMBERG, OF NEW YORK, N. Y.

MANUFACTURE OF GOLF-BAGS.

1,325,692.

Specification of Letters Patent. Patented Dec. 23, 1919.

Application filed June 14, 1919. Serial No. 304,262.

To all whom it may concern:

Be it known that I, ALEXANDER D. CROSS, a citizen of the United States, residing in the city of Newark, State of New Jersey, have invented a new and useful Improvement in the Manufacture of Golf-Bags, of which the following is a specification.

The invention relates to golf-bags, and has for its object to provide a convenient and desirable form of bag wherein the clubs when not in use are protected against loss and theft. The object is also to provide a golf-bag having a cover incorporated therein. The bag comprises a body or outer bag, capable of opening and closing lengthwise and having fastening means, and an inner bag member closed at one end and open at the other and having connections at its open end with the body permitting it to be inverted. Means are also provided in the bottom of the body for shackling the heads of the clubs, so that, even if the cover, which cannot be removed because of its connections with the body, were cut, the clubs could not be withdrawn.

In the accompanying drawings forming a part hereof and in the several views of which similar parts are designated by the same characters of reference:

30 Figure 1 is a front elevation of the bag with the inner member in position to serve as a cover;

Fig. 2 is a side elevation showing the condition of the bag with the inner member lowered;

Fig. 3 is an inside face view of the bag open, with the cover member in the lowered position;

Fig. 4 is a horizontal section near the bottom of Fig. 1;

Fig. 5 is a horizontal section through Fig. 2, at the region of the pivots; and

Fig. 6 is an enlarged fragment of Fig. 5.

The body 1 is preferably of the regulation 45 cylindrical tubular form, closed at the bottom and open at the top. As preferably constructed it comprises two semi-cylindrical frames each formed of two longitudinal members 2, 3 and two curved end members 4, 5 with a covering of fabric or other flexible material 6. Each half has a rigid bottom 7, forming a housing for a ball drawer.

8. The longitudinal members 2 are joined by hinges 9, permitting the halves to be

opened, and the members 3 bear the parts 10, 55 11 of a lock.

An inner, shorter, tubular bag member 12, having one end open and the other end 13 closed, is connected with one of the halves of the body, marked α . Said inner member 60 is preferably formed of flexible material, with a frame composed of two longitudinal members 14 and a ring 15. The ends 16 of the longitudinal members 14 project beyond the open end of the inner bag member, forming lugs for the reception of pivot screws or rivets 17, which fasten to the members 2, 3 of the frame of the half α of the body. These connections are located at a substantial distance below the top of the body; and 70 the inner bag member is of such length that, when it hangs down as a lining, its bottom comes approximately to the bottom of the interior of the body. When swung upward so that its closed end is at the top, it is high 75 enough to accommodate the clubs, which are thus completely housed within the body and inner bag member, now acting as a cover.

The body is opened when the inner member is to be inverted from one position to another, and, when the member is used as a cover, the lock 10, 11 prevents the bag being opened, and the connections 16, 17 in turn prevent the cover from being removed. The clubs, then with their heads down, are embraced by the buckled loop 18 of a strap 19 in the lower part of the half α of the body, thus preventing the clubs being withdrawn even if the cover should be cut. When the bag is fastened the ball drawers are also inaccessible.

Straps 20 on the inner side of the half β are provided for holding clothing or the like.

The bag will stand erect either open or closed, and in either condition will hold the 95 clubs.

What is claimed as new is:

1. A golf-bag comprising a body capable of opening and closing lengthwise, a closed-end cover in the body, and connections securing the cover to the body permitting the cover to be inverted, said connections being substantially below the top of the body, whereby the cover when inverted constitutes an inner bag extending to near the bottom 105 of the outer bag.

2. A golf-bag comprising a body capable of opening and closing lengthwise, a closed-

end cover in the body, and pivot connections between the open end of the cover and the body, said connections being substantially below the top of the body.

5. 3. A golf-bag comprising an outer bag formed of hinged semi-cylindrical frames covered with flexible material, an inner bag, and connections between the inner bag and one of the halves of the outer bag located 10 substantially below the top of the body per-

mitting the inner bag to be inverted to constitute a cover.

4. A golf-bag comprising two longitudinal hinged body halves having means for fastening them, and an invertible lining and 15 cover member closed at one end and pivotally connected at its open end with one of the body halves substantially below its top.

ALEXANDER D. CROSS.
